(57) **CLAIM**

The ornamental design for a drawer for refrigerator as shown and described.

DESCRIPTION

FIG. 1 is a front perspective view of a drawer for refrigerator showing our new design;

FIG. 2 is a back perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof;

FIG. 8 is a bottom plan view thereof; and,

FIG. 9 is a back perspective view of the drawer for refrigerator, shown in an alternative configuration of use.

The broken lines depict portions of the drawer for refrigerator that form no part of the claimed design.

1 Claim, 9 Drawing Sheets
